UNITED STATES PATENT OFFICE.

WILLIAM J. PARKINSON, OF ROCHESTER, NEW YORK, ASSIGNOR TO EASTMAN KODAK COMPANY, OF ROCHESTER, NEW YORK, A CORPORATION OF NEW YORK.

PRESS-GUARD.

1,394,501.

Specification of Letters Patent.

Patented Oct. 18, 1921.

Application filed November 21, 1919. Serial No. 339,751.

To all whom it may concern:

Be it known that I, WILLIAM J. PARKINSON, a citizen of the United States of America, residing at Rochester, in the county of Monroe and State of New York, have invented certain new and useful Improvements in Press-Guards, of which the following is a full, clear, and exact specification.

10 The present invention relates to safety appliances for machinery, and has for its object to provide a simple, cheap and efficient guard for punch presses, which will eliminate a large number of serious accidents to 15 the hands of punch press operators, due sometimes to the operator's negligence, sometimes to worn and otherwise defective clutch mechanism, and sometimes to undue vibration and shaking of the working parts of the 20 press guard. To these and other ends the invention consists in certain improvements and combinations of parts as will be herein-after more fully described, the novel features being pointed out in the claims at the 25 end of the specification.

This invention is an improvement over the punch press safety guard, disclosed in the application of Edmond De Maecker, Serial No. 323,963, filed Sept. 15, 1919.

30 In the drawings in which like reference characters designate like parts:

Figure 1 is a front elevation of punch press equipped with my improved safety guard;

35 Fig. 2 diagrammatically illustrates the position of the parts just as the guard wing returns from swinging across the bed;

Fig. 3 is a plan view of the parts shown in Fig. 2.

40 My invention is applied, in this instance, to a punch press guard of the type shown in Patent No. 1,178,168, MacDonald & Dougherty, Apr. 4, 1916, wherein guards swing across the front of a reciprocating mechanism to prevent the hands of the operator from being placed under the moving parts of the press during a predetermined interval of time. I will, therefore, describe such parts of the guard as pertain to a clear understanding of my invention. Punch press guards are usually designed to function before the ram descends, being actuated either by the foot treadle, or by the ram itself,

there being some types, such as the MacDonald *et al.* type, wherein two guards are 55 operated, one through the foot treadle and the other through the ram. It frequently happens, particularly in the type where the press is operated through a foot treadle, that the rebound of the wing guards and their 60 operative parts will cause a second actuation of the press, and the operator being caught off his guard is injured. The danger, therefore, lies in not holding the safety 65 guards in their inoperative position, until the vibration of the parts entirely cease, and since the interval of time during which the guard is inoperative is very short, it is difficult to provide a satisfactory apparatus to 70 overcome this fault. The vibration in large 75 punch presses and in small rapidly operated presses is excessive because of the necessarily comparatively loose connection between their working parts, as, for instance, is the case with the foot treadle. Generally 80 the operator can depress this member over six inches before the press is operated. My invention is directed particularly to correcting this shock and jar to the guard and press mechanism, and substitutes for the 85 rather complicated locking device controlled through the foot treadle and latch mechanism of the before mentioned application of De Maecker, a very simple and inexpensive shock absorber which operates without 90 complicated springs and latches.

Referring to the drawings, a frame 1, supports a table 2, and an upper frame 3. Frame 3 has a way 4 in which a plunger 5 slides, being moved by an eccentric 6 operated by shaft 7. Power is applied to the fly wheel 8 which normally turns loosely on shaft 7, there being a clutch 9 for keying the shaft to the fly wheel 8. For actuating clutch 9 a shaft 10 extends up from a foot 95 treadle 11, and in this instance is adjusted so that the clutch 9 is operated at the end of the downward movement of foot treadle 11 causing the wheel 8 and shaft 7 to rotate together for one revolution and then to automatically throw out the clutch.

A yoke 12 attached to the upper frame 3 supports the safety mechanism, which consists of a safety guard or wing 13 attached to a shaft 14 which in turn is rotatably 100 mounted on yoke 12 by means of a casting

15 in which there is a bearing for stub shaft 17 fastened in yoke 12. The wing 13 is made of celluloid for convenience, although wire mesh or other material may be used if desired. Casting 15 is attached to the short arm 20 of a bell crank lever 18 through a link 19, the long arm 21 of the bell crank lever being connected by links 22 and 23 to a lever 24 pivoted to the frame 3 at 25. On lever 24 is pivotally attached the upper end of a rod 26, the lower end of which 27 is attached to a shaft 28 carried by the foot lever 11. If desired a second set of parts for operating wing 13 by the ram can be attached to the guard 13 or to a second guard, but for the purpose of illustration of my invention the above described mechanism is sufficient.

The guard 13 is operated in the following manner: work is placed on the female die 30 on table 2, the male die 31 being affixed to plunger 5. The operator having his work in place depresses foot lever 11 slowly. After the foot lever 11 is lowered a portion, say one-quarter of the movement, the rod 26 draws down lever 24, which through links 22 and 23 pull down arm 21 of bell crank lever 18, thus thrusting arm 20 toward the ram so that link 19 will, by thrusting to the left, cause the casting 15 to revolve about shaft 17 in a counter clockwise direction, thereby turning wing 13 so as to cross the path through which work was placed on the bed 2. If the operator's hands had not previously been removed, the wing 13 would remove them by thrusting them from the table 2. By continuing the depression of treadle 11, clutch 9 operated by rod 10 keys shaft 7 and fly wheel 8 together for a revolution, thus causing ram 5 to function and perform an operation on the work. Upon releasing the pressure on treadle 11, the parts all return to their inoperative position, and since forming presses operating at a moderate speed frequently function from forty to sixty times a minute, and simple blanking machines operating much more rapidly, from two to five times a second, it can be readily seen that these movements are rapid and a jerk and jar of considerable magnitude results when the parts are momentarily brought to rest.

I overcome this difficulty by mounting a weight 40, which in this case is cast so as to form a lever, having a bearing 42 to revolve about a stub shaft 43 attached to the yoke 12. This weighted lever rests normally on a stop pin 44, and its movement is limited by a second stop or pin 45, also fastened to yoke 12. To the casting 15, I fasten an arm 46 at such an angle that a large part of the surface 47 on the under side of weight 40 will contact with the lever or arm 46 when it is at rest as shown in Fig. 1. As the wing flies back after an actuation, the arm 46 strikes

the surface 47 and by rocking weight 40 about shaft 43 the weight absorbs the shock of the blow, so that arm 46 comes to a stop with a minimum amount of vibration, and consequently absolutely prevents rebound and jar of the parts attached to and working with the wing 13. In other words, the tendency of the wing guard is, where no shock absorber is provided, to return from its movement across the bed and stop with a jerk, vibrating back and forth from its normal inoperative position, which is shown in Fig. 1, because of the play between the various links, levers, etc. But this jar in the embodiment of my invention shown in the drawings, is transferred from the wing and wing operating mechanism to the lever weight 40, leaving the wing 13 practically still. After the impact of arm 46 with weight 40 pin 44 if necessary limits the upward movement of the weight. I prefer to design my machine so that the weight 40 will normally rotate only to the degree shown in Fig. 2. In returning, pin 45 stops the weighted lever 40 in its normal position. As will be seen from Fig. 1, when arm 46 strikes the weight, the leverage of arm 46 is much less than it is after the weight 40 starts to rotate, as in Fig. 2, but after the first impact, the force exerted by the various parts on lever 46 is considerably less, so that the advantage in leverage is offset by the reduced force. Moreover it should also be noted that the weight lever 40 is designed so that the arm 46 by rocking a comparatively slight distance will rotate the weight a much greater amount than would be the case if the levers were of equal length, and yet the first jar is received by weight 40 when its mechanical advantage is at its greatest because the entire under surface 47 contacts with arm 46. This condition is desirable because it reduces the movement of the parts, to a minimum without decreasing the effectiveness of the shock absorber.

Having thus described my invention, what I claim as new and desire to obtain by Letters Patent is:

1. In a safety guard for punch presses, the combination of a bed, a frame and a ram movable in the frame with a safety guard, operating mechanism for the safety guard adapted to move said guard across the bed and back at each actuation of the ram, a lever for contacting with a part of the safety guard when the same is at rest, the lever alone receiving and taking up the shock from the safety guard when it returns from an actuation.

2. In a safety guard for punch presses, the combination of a bed, a frame and a ram movable in the frame with a safety guard, operating mechanism for the safety guard adapted to move said guard across the bed and back at each actuation of the ram, a le-

- ver for contacting with a part of the safety 5
guard when the same is at rest, said lever
being pivoted to the frame and consisting
of a weight, means on the frame for limit-
ing the movement of the lever, said weighted
lever receiving the shock transmitted from
the safety guard upon its return from an ac-
tuation, thereby preventing vibration of the
safety guard.
- 10 3. In a safety guard for punch presses, the
combination of a bed, a frame and a ram
movable over the bed with a swinging safety
wing, means for moving the safety wing, an
arm attached to the safety wing and a lever
15 attached to the frame, the arm being
adapted to contact with a lever when the
safety wing is at rest, the lever alone pre-
venting the rebound of the safety wing as
it comes to rest.
- 20 4. In a safety guard for punch presses,
the combination of a bed, a frame and a ram
movable over the bed with a swinging safety
wing, means for moving the safety wing, an
arm attached to the safety wing, a weighted
25 lever pivoted to the frame, said wing arm
and said lever being in contact when the
wing guard is at rest, the weighted lever re-
ceiving the shock or vibration from the
wing arm as the wing guard comes to rest.
- 30 5. In a safety guard for punch presses,
the combination of a bed, a frame and a ram
movable over the bed with a swinging safety
wing, means for moving the safety wing, an
arm attached to the safety wing, a weighted
35 lever pivoted to the frame, stops on the
frame to limit the movement of the weighted
lever, the wing arm striking the lever and
passing thereto the shock resulting from the
wing guard coming to rest after an actua-
40 tion, and the stop preventing the weighted
lever from returning the shock to the wing
guard.
6. In a safety device for punch presses,
the combination of a bed, a ram, and ram
45 moving mechanism with a safety guard
adapted to cross a side of the bed, an arm
fastened to the safety guard and a weight
pivoted to the frame, the said arm and lever
being positioned so as to give the weight
50 the mechanical advantage when a force is
first exerted by the arm on the lever, and
then to give the arm the mechanical advan-
tage over the weight as the force is further
exerted, so that the weight will sustain the
55 blow and ease the impact of the arm as the
safety guard comes to rest after an actua-
tion.
7. In a safety device for punch presses,
the combination of a bed, a ram, and ram
60 moving mechanism with a safety guard
adapted to cross a side of the bed, an arm
fastened to the safety guard and a lever
pivoted to the frame, the arm adapted to
contact with a portion of the lever when the
65 safety guard is at rest, a stop on the frame
for holding the lever in a predetermined po-
sition, said arm striking said lever as the
wing guard returns from an actuation, the
wing guard and arm being rotated beyond
70 their normal position of rest, the said lever
receiving the resulting vibration of the wing
guard.
8. In a punch press safety device, the
combination of a frame, a bed, a ram inter-
mittently operating over the bed with a wing
75 guard pivoted to the frame, mechanism for
moving the guard in timed relation to the
ram, an arm attached to the guard, and a
lever pivoted to the frame, the arm tending
to rock the lever when the wing guard 80
swings past its position of rest in one direc-
tion.
9. In a punch press safety device, the com-
bination of a frame, a bed, a ram intermit-
tently operating over the bed with a wing
85 guard pivoted to the frame, mechanism for
moving the guard in timed relation to the
ram, an arm attached to the guard, and a
lever pivoted to the frame, the arm tending
to rock the lever when the wing guard 90
swings past its position of rest in one direc-
tion, said lever limiting the movement of the
wing guard as it comes to rest.
10. In a punch press safety device, the
combination of a frame, a bed, a ram inter-
mittently operating over the bed with a wing
95 guard pivoted to the frame, mechanism for
moving the guard in timed relation to the
ram, an arm attached to the guard, and a
lever pivoted to the frame, the lever 100
having a flat surface contacting with the
arm tending to normally hold the arm and
thereby the wing guard steady in its inop-
erative position.
11. In a punch press safety device, the
combination of a frame, a bed, a ram inter-
mittently operating over the bed with a
wing guard pivoted to the frame, mecha-
105 nism for moving the guard in timed rela-
tion to the ram, an arm attached to the
guard, and a lever pivoted to the frame, the
lever having a flat surface contacting with
the arm tending to normally hold the arm
110 and thereby the wing guard steady in its
inoperative position, and to absorb the shock
resulting from the wing guard suddenly
115 coming to rest, preventing the wing guard
from oscillating back and forth from its in-
operative position.
12. In a punch press guard, the combina-
tion of a frame, a ram and ram operating
mechanism with a swinging wing guard, a
foot treadle for operating the ram operat-
ing mechanism, and means for swinging the
wing guard controlled by the foot treadle, 120
and a weight pivoted to the frame so as to
be struck by the wing guard at one end of
its swing, the vibration of the wing guard
being taken by the weight, so that the jar
125 and back lash of the wing guard cannot re-
130

act through the foot treadle to the ram operating mechanism, causing accidental tripping of the ram.

13. In a punch press guard, the combination of a press comprising a frame, a bed, a ram movable in the frame with a safety guard pivoted to the frame and adapted to cross a side of the bed when the

ram is moved, a mechanism for moving the wing guard, and means, independent of the guard operating mechanism, for absorbing the vibration of the returning safety guard comprising a weight on the end of a lever.

Signed at Rochester, New York, this 18th day of November, 1919.

WILLIAM J. PARKINSON.
